UNITED STATES PATENT OFFICE.

GEORGE J. WINTER, OF BUFFALO, NEW YORK, ASSIGNOR OF ONE-HALF TO HARRY G. PHILLIPS, OF BUFFALO, NEW YORK.

PNEUMATIC HEEL.

1,399,836.

Specification of Letters Patent. Patented Dec. 13, 1921.

Application filed February 19, 1921. Serial No. 446,287.

To all whom it may concern:

Be it known that I, GEORGE J. WINTER, a citizen of the United States, residing at Buffalo, in the county of Erie and State of New York, have invented new and useful Improvements in Pneumatic Heels, of which the following is a specification.

My present invention pertains to cushion heels, and it contemplates the provision of 10 a heel that is primarily adapted for use in connection with new shoes, and is capable of ready and easy application to a shoe; one that is inexpensive to produce and repair; one that overcomes the objectionable "run over" condition so prevalent in cushion heels now in use and one through the medium of 15 which comfort to the wearer is assured and a neat appearance is at all times given to the shoe.

20 My invention also contemplates the provision of a heel that may be easily and inexpensively repaired and at the same time a heel that produces the cushioning effect of a pneumatic chamber.

25 The invention in all of its details will be fully understood from the following description and claims when the same are read in connection with the drawings forming part of this specification in which:

30 Figure 1 is a side elevation of a portion of a shoe and showing my novel heel in longitudinal section as applied to the shoe.

Fig. 2 is a rear elevation and showing my heel in transverse section as applied to the 35 shoe.

Fig. 3 is a longitudinal section of the lower lift of my novel heel.

Fig. 4 is a top plan view of the upper portion of the heel and showing the smooth 40 upper face thereof.

Fig. 5 is a view similar to Fig. 4 but showing the opposite or lower surface of section 1.

Fig. 6 is a top plan view of the lower lift 45 of the heel.

Similar numerals of reference designate corresponding parts in all of the views of the drawings.

The heel of my present invention comprises an upper section 1 and a lower section 2, and said sections are by preference formed of rubber or equivalent material as is the case with cushion heels now in the market. The sections 1 and 2 are rigidly

retained to each other by cementing them 55 together.

The surface of the section 1 that bears against the shoe is perfectly smooth (Fig. 4), and on its lower surface said section 1 is provided with a chamber or cavity 5 and in 60 the direct center of the section. This cavity extends inwardly to approximately the center of the section 1 with respect to the thickness thereof.

Communicating with and extending radially from the cavity 5 are equidistant channels 6 and these channels are proximately one half the depth of the cavity 5.

At its forward and rear ends the lower surface of the section 1 is provided with 70 comparatively large apertures 6, and the said surface is also provided with nail receiving apertures 9 for the reception of nails 11 and the interposed washers 10 (Fig. 2).

By reference particularly to Figs. 3 and 6 75 of the drawings it will be apparent that the lower lift 2 has a perfectly flat ground-gripping surface and in its upper face I provide integral barbs or projections 4 and a comparatively large integral boss 7. 80

In the practical use of the invention, the section 1 is secured to a shoe in the ordinary well known manner with the chamber 5 directed away from the shoe. The lift 2 is then cemented to the under side of the section 1 with the projections 4 resting in the apertures 6. Manifestly the sections when thus arranged have the boss 7 resting in the chamber 5 of the section 1 and thus a pneumatic space 8 is formed around the 90 boss 7 in the chamber 5.

When the wearer of a shoe equipped with my novel heel places his foot upon the ground the weight will be thrown on the boss 7 that bears at its upper end on the upper wall of the chamber 5 and thus running over of the lift 2 is precluded. In other words the heel will be forced flat against the ground.

Pressure exerted on the boss 7 will cause 100 a pneumatic air cushioning effect to be formed in the chamber 7 and resiliency will be imparted to the heel because of the pulling away of the boss from the upper wall of the cavity 5 on the initial upward movement of the heel from the ground. Moreover the radial grooves or channel 6 will 105 assist in cushioning the upward movement

(which is kindred to flattening) of the boss 7 when the weight of the wearer is placed on the heel.

The construction illustrated and described 5 assures perfect wear in an even manner of the flat surface of the lift 2 and when this lift is worn down to the lower surface of the section 1, the said lift or what remains of it may be readily removed and replaced 10 with a new lift by a person even though said person is unskilled in shoe-repair work.

The section 1 forms a permanent part of the shoe and will outlast the upper and sole 15 of the said shoe. However, when the lift wears out to an appreciable extent the expense of replacing the lift is quite small compared to the cost of an entire new heel.

The heel as a whole comprises no delicate 20 or inoperative members and because of its construction it may be built up with a new lift and thus the heel greatly adds rather than detracts from the finished appearance of a shoe at all times, and at the same time wear of the lift 2 will not expose the securing 25 nails and marring of a highly polished surface or injure expensive rugs and the like.

Having described my invention, what I claim and desire to secure by Letters-Patent is:—

30 1. In a heel the combination of an upper section of resilient material, a central chamber formed in the lower face of said section, radial grooves surrounding and communicating with the chamber and of slightly less 35 depth than the depth of said chamber, apertures formed in said lower face of the section, a lift adapted to be cemented to the first section, a nipple formed in the upper face of the lift and constructed and arranged 40 to seat in the chamber and bear against the upper wall thereof, and portions on the lift adjacent the nipple that seat in the apertures of the section.

2. In a heel for the purpose specified, the 45 combination of two opposing and removable

sections, a cavity formed in the center of one section and extending approximately one half the thickness of the section, radial equi-distant channels surrounding the cavity and communicating therewith and approximately one half the depth thereof, apertures formed at the front and rear of the upper section adjacent the cavity, comparatively small apertures adjacent the first apertures, a boss formed on one of the sections and adapted to seat in the cavity of the first section and members formed integral on the last section adjacent the boss and adapted to seat in the first named apertures of the first section to assist in preventing movement of the sections with respect to each other.

3. A heel comprising two removable sections, a cavity formed in the center of one section, channels surrounding the cavity and communicating therewith and a boss formed in the other section and adapted to rest in the cavity.

4. In a heel for the purpose specified, the combination of an upper section having a smooth surface and a cavity formed in the opposing surface, channels formed in the last named surface, apertures for fastening means provided in the sections, other apertures adjacent the first apertures and a lift 75 adapted to be removably secured to the section, and having one smooth surface and a boss formed in its other surface and adapted to enter the cavity of the upper section, and integral portions arranged adjacent the boss 80 and adapted to rest in the apertures of the upper section.

In testimony whereof I have hereunto set my hand in presence of two subscribing witnesses.

GEORGE J. WINTER.
